UNITED STATES PATENT OFFICE.

JAY ELLIS CRANDALL, OF CHERRY VALLEY, ILLINOIS.

GRINDING-MACHINE.

1,073,097.

Specification of Letters Patent. Patented Sept. 16, 1913.

Application filed April 10, 1913. Serial No. 760,163.

To all whom it may concern:

Be it known that I, JAY ELLIS CRANDALL, a citizen of the United States, residing at Cherry Valley, in the county of Winnebago and State of Illinois, have invented certain new and useful Improvements in Grinding-Machines, of which the following is a specification.

This invention relates to grinding machines and more particularly to that type of machine in which it is desired to grind a surface on a thin article of tempered material without drawing the temper from the article.

The object of this invention is to construct a grinding machine of this type adapted for use in the forming of corset-stays such as are described in my patent application for corset-stays, Serial No. 751,526, filed Feb. 20, 1913. In the manufacture of this type of corset-stay it is desired to form a portion of the length of the stay gradually tapering toward one end and leaving an enlarged head at said end so that the tapered portion will be more flexible than the body portion of the stay and the enlarged head will serve as a holding means to retain a protecting cap fastened thereto. I accomplish this object by providing means for drawing a stay between two adjacent grinding wheels so as to grind with the adjacent peripheries; providing the grinding wheels with mountings through which certain desired movements are resultant; and by utilizing certain automatic devices to control the co-operation of the driving means and both the stay carrying and grinding means.

A further object is to provide anti-vibrator means to stop vibrating of the stay during the course of its grinding.

In the accompanying drawings, Figure 1 is a plan view of my novel grinding machine, showing the machine in its inoperative position. Fig. 2 is a view in elevation of the drive side of the machine. Fig. 3 is a longitudinal vertical section on the line 3—3 of Fig. 1, showing a corset-stay mounted in the vise. Fig. 4 is an enlarged plan section on the line 4—4 of Fig. 3 showing the vise moved to the end of its movement. Fig. 5 is a detail plan section on the line 5—5 of Fig. 2, showing the cam for actuating the grinding spindles. Fig. 6 is a transverse vertical section on the line 6—6 of Fig. 1. Fig. 7 is a vertical section on the line 7—7 of Fig. 6. Fig. 8 is a plan section

on the line 8—8 of Fig. 2 illustrating the parts in a position when the carriage has just started its forward feed strike. Fig. 9 is a vertical section on the line 9—9 of Fig. 1.

The base 10 of the machine is supported by standards 11, has two centrally disposed longitudinal ways 12 formed therewith, and has oppositely extending wing sections 13. Mounted slidably upon the ways 12 is the carriage 14 in the form of an open top reservoir having extending longitudinally from its straight end two arms 15 and 16.

Mounted upon the extending sections 13 are supports 17 and 18, the support 17 being secured fixedly in position and the support 18 being movably mounted, movable from the pivot 19 of its arm 20 from the base 10, as is seen in Fig. 7, and is held in position by the clamp 21 bolted to the base 10, having an adjustable bearing plate 22 engaging an extension 23 of the support. The upper ends of these supports are formed with horizontal ways 24 upon which are slidably mounted spindle bracket supports 25 having upstanding bracket portions 26. Bolted to said bracket portions are the spindle supports 27 each having an upper and lower vertically disposed bearing 28 and 29 journaled in the bearings are spindles 29 having fixedly mounted at their center portion the drive pulleys 30 and at their lower ends the grinding wheels 31 of a suitable composition of material, the spindle supports capable of being raised from position by removing their inner supporting bolts and being pivoted from their outer supporting bolts. Screws 32 (Fig. 6) are fixedly carried by supports 17 and 18 and have hand feed nuts 33 rotatably mounted thereon, the spindle bracket supports 25 being movable with the hand nuts 33 by the end plate connections 34, so that by rotating the hand nuts 33 the grinding wheels are adjusted toward or away from one another. Journaled brackets 35 bolted to the rear end of the base 10 carry a shaft 36 upon which is mounted idler pulleys 37 adapted to guide driving belts (not shown) which are adapted to rotate the spindle pulleys 30 at a high rate of speed. A vise 38 of a suitable construction is fixed to the reservoir 14, having in this case shown one with a rigid jaw 39 and an adjustable jaw 40 actuated by the hand lever 41, the vise being so disposed that when a corset-stay is clamped horizontally

100

105

110

therein in the inoperative position of the machine as in Fig. 1, said stay will lie intermediate the grinding wheels, projecting beyond their center as is clearly shown in Fig. 3.

5 Mounted in journal brackets 42 to the underside of the base is the drive-shaft 43 which carries (Fig. 9) a drive pulley 44 loosely mounted between the fixed collars 45, a smaller drive pulley 46 loosely mounted, held from longitudinal movement by the guide bracket 47 and having a female clutch member 48 formed therewith, a clutch 49 splined to the shaft having a male clutch portion adapted to engage member 48 and lug clutch-members adapted to engage corresponding lugs on pulley 44, and a screw-worm 50 fixedly mounted upon the shaft. A worm-gear 51 is rotatably mounted to the underside of the base, meshing with screw-worm 50, and a crank-arm 52 operable with the worm-wheel is connected to the end of arm 15 through bolt 53; thus rotation of the drive-shaft will reciprocate crank 52 and feed the carriage 14 longitudinally upon the ways 12.

10 A cam face 54 (Fig. 5) is fixed adjustably with the outer side of carriage 14 adjacent support 18, and bolted to said support is a cam follower plate 55 which is held yieldingly into contact with the face of the cam. This contact is yielding in the sense that the support 18 is pivotally mounted at 19 and the bell-crank lever 56 pivotally carried at 57 has an upstanding arm 58 held into contact with the said support by the weight 59 at the lower arm of the bell-crank, thus always holding the plate 55 into contact with the cam face but leaving it free to move in the opposite direction. Movement of the support 18 following the cam face moves the grinding wheel carried thereby to and away from the fixed wheel. Fig. 5 shows the inoperative position of the machine with the cam follower on the highest portion 60 of the cam which maintains the grinding wheels spaced apart inoperatively, but when the carriage 14 is fed forward the cam follower will move to the 15 tapered face 61 and follow the gradual taper thereof, and thus bring the grinding wheels closer together, gradually, as they perform their grinding operation.

15 A clutch lever 62 is pivoted at 63 to the base 10, has an operating handle 64 and an arm 65 which carries a roller in engagement with the clutch 49. A spring 66 tends to hold the clutch lever with the clutch in engagement with the female clutch 46, and is adapted to be disengaged from the clutch lever by the cam 78 carried by arm 16; but with the machine in its operative position as in Fig. 1 the adjustable stop 67 carried by carriage 14 will contact the face 20 68 of the lever and hold it from engaging

said clutch members. When the lug clutch is engaged with pulley 44 the catch 69 pivoted to the base will be raised by spring 70 and hold the parts in such engagement as seen at Fig. 8.

20 A continuous feed of water is supplied to the grinding wheels while in operation, through pipe 71 carried by the support 72, the water being suitably drained through the outlet 73, and a covering (not shown) 75 is provided for the open top of the carriage to confine the water from splashing onto adjoining parts.

25 Anti-vibrator rods 74 and 75 are carried through the support 72, positioned at opposite sides of a stay being ground, and at each side of the grinding point of the wheel. A water baffle-plate 76 is carried by rod 75 to help direct sprayed water to be confined to the grinding wheels.

30 In the operation of the machine, with the several operable parts in the position as shown in Fig. 1, grinding wheels 31 will be rotated as above stated, and both clutch members 44 and 46 will be rotated in opposite directions without affecting any 35 of said operable parts. With a corset-stay mounted in the vise as is seen in Fig. 3, the hand lever 64 will be pulled forward as shown in Fig. 8, thereby driving shaft 43

40 through pulley 44 and being held in such position by the catch 69. Rotation of the drive-shaft will feed the carriage 14 forward through the worm-gear 51 and crank 52, thereby allowing plate 55 to follow the 45 cam face 61 and bring the grinding wheels into grinding contact with the sides of the corset-stay at a point, as illustrated in this case in Fig. 4, at 77. As the feed of the carriage continues the grinding wheels will 50 be brought closer together grinding a gradual taper to the end of the stay until the very end of the stay has been ground, when the traveling cam 78 will contact catch 68, disengaging it from lever 62 and allowing the spring 66 to throw the clutch 55 into engagement with member 46 and thereby reverse the drive direction of shaft 43. At this point the crank 52 does not reach 55 the top of its stroke so that it will return the carriage, allowing the grinding wheels to polish the ground surface of the stay. When the high point 60 in the cam has been reached the wheels will be parted as above described and the stop 67 will contact face 68 of the lever 62, thereby disengaging the clutch members and stopping the operation of the operable parts.

60 During the feed strokes of the carriage the stay, because of its light body, is often caused to vibrate with such force that if it were not for the anti-vibrator rods 74 and 75 the stay would be immediately severed by the grinding wheels.

65 In the present embodiment of my grind-

ing machine I have illustrated but one of the grinding wheels as being mounted to follow the contour of the grinding operation, and it will be seen that both wheels 5 might be so mounted and to follow cam movements of whatsoever design desirable.

The entire operation of the machine when once set in motion is automatic thus producing grinding with results of a high efficiency and the various adjustments for accurate setting and control of the grinding wheels.

With a grinding machine of this type vary narrow and flexible articles may be 15 ground without drawing the temper therefrom, and furthermore, through control of the grinding wheels, varying shaped faces may be obtained.

I claim as my invention.

20 1. In a grinding machine, the combination with a reciprocable work holding carriage, of a grinding wheel support movable toward and away from work carried by said carriage, a grinding wheel for the support, 25 a grinding pattern for governing the movements of said wheel support, and mechanism for moving said wheel support toward said work simultaneously with the reciprocation of the carriage in one direction, the 30 support guided by said pattern, and for moving the support retracing said pattern, away from said work and simultaneously with the return reciprocatory movement of said carriage.

35 2. In a grinding machine, the combination of two grinding wheels positioned with their grinding faces located one opposite the other, a reciprocable work holding carriage adapted to carry an article intermediate 40 said grinding faces, and mechanism for moving one of said wheels toward and away from the other to operate upon said article simultaneously with the reciprocation of said carriage, said mechanism moving one 45 of said grinding wheels toward the other in a predetermined movement during the reciprocation of the carriage in one direction, and away from said other wheel corresponding to said predetermined movement and 50 simultaneously with the return of the carriage from its said movement, whereby said article will be ground to a form corresponding to the predetermined movement of the one grinding wheel toward the other and reground to said form with said movement of the grinding wheel away from the other.

3. In a grinding machine, the combination with two grinding wheels mounted with their grinding faces located one opposite the 60 other, of means for carrying an elongated article intermediate said grinding faces and for moving the article between said faces in the direction of its elongation, and anti-vibrator means located adjacent the said 65 grinding faces at one side of the article and

adapted to contact the article when the article vibrates during its said movement between the grinding faces.

4. In a grinding machine, the combination of two grinding wheels mounted with their grinding faces positioned one opposite the other, a work holding carriage adapted to carry an elongated article of a substantially uniform thickness intermediate said grinding faces, means for moving 70 the carriage and drawing the article between said faces, means for simultaneously and positively feeding said grinding wheels toward each other to grind a portion of the article to a gradual taper in the direction of 75 its elongation, and discontinue said taper at a predetermined point to leave said end substantially with its uniform thickness.

5. In a grinding machine, the combination of a work holding carriage adapted to 80 carry an elongated article of substantially a uniform thickness, a grinding wheel adapted to operate upon a face of said article, and means for positively feeding said grinding wheel in its operation upon the article to 85 grind a gradual taper thereon toward one end of the article.

6. In a grinding machine, the combination of a work holding carriage adapted to carry an article to be ground, a grinding 90 wheel, a support therefor mounted to move in a plane parallel with the plane of rotation of said wheel to move the wheel into and out of contact with the article to be ground, means for feeding the carriage to 95 carry the article across the face of the wheel, and means cooperating with the carriage and wheel support and operable through the movement of said carriage to control the movement of said wheel support to and away 100 from the article being ground.

7. In a grinding machine, the combination with a reciprocable work holding carriage and a grinding wheel, of driving 110 mechanism for reciprocating the carriage in opposite directions, operating means coöperating with said driving means to control the operation of said driving means, and means for automatically actuating said operating means at a predetermined point 115 in the reciprocation of said carriage to reverse the reciprocation.

8. In a grinding machine, the combination of a reciprocable carriage, two grinding 120 wheels mounted with their grinding faces positioned one opposite the other and movable toward and away from each other, a work holding means mounted on the carriage and adapted to carry an article to be ground intermediate said grinding faces, 125 and in contact therewith, means for reciprocating said carriage, drawing the article between said faces, and pattern regulated mechanism for controlling the movement of said grinding wheels in their contact with 130

1
the article to feed the wheels together to 5
grind the article upon the carriage being
reciprocated in one direction, and move the
grinding wheels to retrace said grinding
upon the carriage being reciprocated in the
opposite direction.

9. In a grinding machine, the combination
of two grinding wheels mounted with
their grinding faces positioned one opposite
10 the other, means for carrying an article to
be ground with one end of the article free
and located intermediate said grinding
faces, and adjustable means located fixed
15 in relation to the grinding wheels, adjacent
opposite sides of the article in non-connec-
tion therewith to prevent said article from
vibrating.

10. In a grinding machine, the combination
of two grinding wheels mounted with
20 their grinding faces positioned one opposite
the other, means for carrying an article to
be ground with one end of the article free
and located intermediate said grinding
faces, and anti-vibrator means located on
25 each side of the grinding contact of said
grinding faces with the article and spaced
at opposite sides of the article.

11. In a grinding machine, two grinding
wheels mounted with their grinding faces lo-
30 cated one opposite the other and adapted to
operate upon an article interposed therebe-
tween, and anti-vibrator means spaced from
the article and located adjacent the adj-
acency of said grinding faces.

35 12. In a grinding machine, the combina-
tion with a reciprocable work holding car-
riage and a grinding wheel, of two clutch
members oppositely driven, a shiftable le-
40 ver mechanism coöperable with both of said
clutch members and having a driving con-
nection with said reciprocable carriage, the
engagement of said mechanism with one of
45 the clutch members causing the carriage to
be reciprocated in one direction and the en-
gagement with the other causing the car-
riage to be reversed in its reciprocation.

13. In a grinding machine, the combina-
tion with a reciprocable work holding car-
riage and a grinding wheel, of two clutch
50 members oppositely driven, a shiftable le-
ver mechanism coöperable with both of said
clutch members and having a driving con-
nection with said reciprocable carriage, the
engagement of said mechanism with one of

the clutch members causing the carriage to 55
be reciprocated in one direction, means for
holding the said mechanism in said engaged
position, and means for disengaging said
mechanism at a predetermined point in the
reciprocation of said carriage to allow said 60
mechanism to be engaged with the other
clutch member.

14. In a grinding machine, the combina-
tion with a reciprocable work holding car-
riage and a grinding wheel, of reversible 65
driving mechanism for reciprocating said
carriage in opposite directions, operating
means coöperating with said reversible
driving means and adapted to control the
operation of said driving means to the car-
70 riage, and a member movable simultane-
ously with the reciprocable movement of
said carriage and adapted to actuate said
operating means at a predetermined point
in the reciprocation of said carriage. 75

15. In a grinding machine, the combina-
tion with a reciprocable work holding car-
riage and a grinding wheel, of driving 80
mechanism for reciprocating the carriage
in opposite directions, operating means co-
operating with said driving means to con-
trol the operation of said driving means,
means for automatically actuating said op-
erating means at a predetermined point in
the reciprocation of the carriage to reverse
85 the reciprocation, and means for automatic-
ally stopping said driving mechanism at
a predetermined point in said reverse recip-
rocation.

16. In a grinding machine, the combina-
tion with a grinding wheel and a work hold-
ing carriage reciprocable relative thereto, of
driving mechanism for reciprocating the
carriage in opposite directions, and means 90
for automatically reversing the reciproca-
tion of the carriage at a predetermined point
of the reciprocation in one direction and
for stopping the reciprocation at a predeter-
mined point in the said reverse reciproca-
tion of the carriage. 95

100
In testimony whereof I have hereunto set
my hand in presence of two subscribing
witnesses.
